[57] CLAIM

The ornamental design for a remote controlled searchlight
for vehicle, boat, or the like, as shown and described.

DESCRIPTION

FIG. 1 is a top, front, right side perspective view of a
remote controlled searchlight for vehicle, boat or the
like showing our new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof, the left
side being a mirror image.

FIG. 1

FIG. 2

FIG. 3

FIG. 5

FIG. 4

FIG. 6
